(57) CLAIM

The ornamental design for a wrist watch case with band, as shown and described.

DESCRIPTION

FIG. 1 is a perspective view thereof,

FIG. 2 is a front elevational view thereof,

FIG. 3 is a rear elevational view thereof,

FIG. 4 is a top plan view thereof,

FIG. 5 is a bottom plan view thereof,

FIG. 6 is a left side elevational view; and,

FIG. 7 is a right side elevational view thereof.

The broken lines in the drawings are used to show portions of the wrist watch case with band that do not form part of the claimed design.
